UNITED STATES PATENT OFFICE.

WILLIAM ERASTUS WILLIAMS, OF CHICAGO, ILLINOIS, ASSIGNOR TO AMERICAN STEEL FOUNDRIES, OF CHICAGO, ILLINOIS, A CORPORATION OF NEW JERSEY.

DEMOUNTABLE-RIM DISK WHEEL.

Application filed August 4, 1920. Serial No. 401,107.

To all whom it may concern:

Be it known that I, WILLIAM ERASTUS WILLIAMS, a citizen of the United States, a resident of Chicago, in the county of Cook and State of Illinois, have invented a new and useful Improvement in Demountable-Rim Disk Wheels, of which the following is a specification.

My invention relates to disk wheels, for automobiles, using pneumatic tires carried by a rim which can be attached to or removed from a felloe.

The object of the invention is to provide a very light, cheaply constructed, disk wheel body that may be securely fastened to a felloe, and that offers great resistance to both tension and compression.

Reference will be had to the accompanying drawing in which Figure 1 is a front elevation of the wheel.

Figure 2 is a side sectional elevation.

Figure 3 is a sectional detail of a part of the rim.

In the drawing 1 indicates an ordinary demountable rim for a pneumatic tire. 2 an ordinary hub, 3 a brake drum, 4 a steel felloe, 5 the inner of two disks forming the wheel web, 6 the outer disk, 7 clip bolts, 8 demounting clips, and 9 the clamping wedge ring ordinarily employed with demountable rims of this type.

10 designates a rear hub-flange, here shown as integral, 11 a front clamping flange, and 12 bolts clamping together the drum and flanges. The flanges have on their inside, opposing, faces sinuous marginal grooves which pass alternately inside and outside the holes for consecutive bolts. The disks 5, 6 have like sinuous internal grooves and corresponding external ribs which fit in the disk grooves, respectively, where they are held by a correspondingly sinuous ring or tube 13 between the disks.

The disks are provided, radially outside the flanges 10, 11, with annular swells 15, 16 which give the disks, as a whole, slight elasticity and at the same time stiffen the portions near the flanges 10, 11 and prevent movement at this point. The sinuous construction secures the disks to the hub in such manner that the union has approximately as great resistance to both tensile and compressive strains as the body of the disks.

The metal of the disks extends beyond the fastening point 14 and terminates far down

on the flanges as indicated by 16. This extra metal in beyond the sinuous flange 13 gives added resistance against the metal of the disks pulling around and under the edges of the sinuous ring 13, for in any movement 60 of this kind the extra metal of the disk beyond the zone of the sinuous fastening would have to be stretched or compressed in order to accommodate the variations in the circumference due to larger or smaller diameters. 65

The margins of the disks 5 and 6 are turned over the front flange 17 of the felloe as is indicated by 18 and the wedge ring 9 bears on the margins of the disks holding them down on to the front flange 17 on the 70 surface 19. The bodies of the disks are curved under the inside front corner of the felloe as is indicated by 20 and the lower or inner edges 21 of the clamping blocks 8 bear directly on to the body of the disks 75 opposite the inside corner 28 of the felloe. 4. The inside flange of the felloe is indicated by 22 and it is provided with a turned over edge 23 for furnishing the bearing on the inside for the rim 1.

The edges of the disks where they turn over the front flange 17 of the felloe are riveted or spot welded through this flange 17 as is indicated by 24 and thus the metal of the disks is held against being withdrawn 85 over the edge of the flange 17 of the felloe.

The central load line of the wheel is indicated by 25 and this load line is fixed by the normal arrangement of a wooden wheel. The location of the flange 10 of the hub is 90 substantially the same location of the inside of the zone of the spokes of a normal wooden wheel assembly.

The greatest shocks that wheels are exposed to are skid shocks rather than rolling 95 load shocks and hence it is most desirable to provide adequate strength for skid shocks avoiding unnecessary weight of material.

The connection of my disks with the front edge of the felloe 4 as is indicated furnishes 100 ample direct load carrying capacity and at the same time gives a greater skid shock resistance than might be the case where the disks fasten to the felloe near the load line 24, the separation of the disks at the hub 105 and their association at the rim being the same as here shown.

The wedge ring 9 bearing directly upon the margins of the disks serves to take direct load strains without their being trans- 110

mitted through the fastening of the disks to the felloe parts so that the amount of load that is necessarily carried through the fastening of the disks with the felloe may be 5 said to be represented by what is carried by the flange 22 of the felloe 4 or the inside flange of the felloe. This flange 22 is deeper than the flange 17 and taken in connection with the body of the felloe 4 is amply strong 10 to transmit the whole load without any appreciable distortion so that the felloe thus connected with my disks operates almost as a unitary structure might act.

The sinuous fastening of the disks to the 15 hub flanges as indicated by the grooves 14 allows the pressure of the clamping bolts 12 to be approximately uniformly distributed to the ring or spreader 13 and at the same time makes a positive fastening against the 20 rotation of the disks in relation to the hub flanges. This sinuous groove in the flanges of the hub being curved in outline as shown permits the slot to be milled in a turning lathe having a tool post movement under 25 the influence of a cam, which permits the machining of said groove with little or no expense more than is occasioned with a uniform circle groove. The fastening of the disks to the hub flanges at the margins of 30 the latter distributes strains on the circumferences of circles much larger than the hub barrel where fastening is more commonly made and so gives much greater strength, the resisting metal being greatly increased 35 in cross sectional area.

The rear integral flange 10 of the hub is reinforced by filler blocks 26 and for the purpose of lightening the material there are apertures 27 in this rear flange between 40 the filler blocks 26. These apertures are covered over by the body of the brake drum as shown.

The front disk being curved outward and over the front edge of the felloe, makes a 45 perfectly smooth clean arrangement for washing the wheel on the front face, which is a great desideratum.

What I claim is:—

1. In devices of the class described, the 50 combination with a felloe of outwardly open channel form, of a wheel body of the disk type having its peripheral zone bent laterally over and closely fitting one flange of

the felloe, a rim encircling said flange, a wedge interposed between the rim and flange 55 and resting against the inwardly bent zone, and means for urging the wedge inward.

2. The combination with a felloe in the form of an outwardly open channel, of companion wheel disks forming marginally a 60 double web and bent together closely around the margin of one of the felloe flanges and in contact with both faces of the same.

3. The combination with a metal felloe having in radial cross section the form of 65 an outwardly open channel, of a wheel body of the disk type having its peripheral zone fitting against one face of the felloe flange, doubled back closely around the flange edge and inwardly along the opposite face, a rim 70 encircling the felloe, blocks for rigidly clamping the felloe and rim relatively, and bolts for exerting the clamping force.

4. A metal felloe of outwardly-open channel shape in radial section, wheel disks having 75 their outer zones in lateral contact and doubled back over the edge of the felloe flange into the channel to form with the flange, in radial section, a compound web, and means for securing the disks and felloe 80 against relative movement.

5. In a wheel of the class described, a felloe, a plurality of disks forming the web of the wheel, said disks inseparably secured to each other and to the front side of the 85 felloe and diverging in passing inwardly from the rim, a rim encircling the felloe, bolts passing through the felloe and disks, and a wedging device urged by the bolts into position for rigidly holding the rim, 90 felloe, and disks against relative movement.

6. The combination with a felloe, of wheel body disks resting against the front side of the felloe and bent laterally inward at each margin thereof, clamping devices fitting the 95 inwardly bent portions at the felloe margins, and bolts binding said devices to the felloe.

Signed at Chicago, in the county of Cook and State of Illinois, this 28th day of July, 100 1920.

WILLIAM ERASTUS WILLIAMS.
